UNITED STATES PATENT OFFICE.

EDMUND S. WILGUS, OF PRINCETON, NEW JERSEY.

DESIGN FOR A RAILROAD-FROG.

SPECIFICATION forming part of Design No. 33,341, dated October 9, 1900.

Application filed December 22, 1899. Serial No. 741,334. Term of patent 7 years.

To all whom it may concern:

Be it known that I, EDMUND S. WILGUS, a citizen of the United States, residing at Princeton, in the county of Mercer and State of New Jersey, have invented and produced a new and original Design for Railroad-Frogs, of which the following is a specification, reference being had to the accompanying drawings, forming a part thereof.

10 Figures 1 and 2 are perspective views of the frog from different points. Fig. 3 is a plan view. Fig. 4 is a perspective view showing bottom of frog.

As shown in the drawings, the design consists of a body having its upper surface on one side convex, as shown at A, said convexed surface terminating in an inclination B, which reaches to the end of the frog. At approximately the center of the body and 20 longitudinally thereof is a rib C, triangular in cross-section for a portion of its length, the terminus of the rib having a flattened upper surface, which extends from the terminus of the angular contour to the end of the frog.

This rib is tapered transversely as it approaches the end. A rib D projects from the edge of the body upwardly, said rib merging with the body at the terminus of the incline portion of said body. From the point of merger of the rib and body to the end of said body a slight groove is produced, said groove indenting the triangular rib heretofore described. The side of the body is provided with a longitudinal groove, as shown at G. The under side of the body is recessed, as shown at R, and the recessed portion is provided with longitudinal ribs S. A flat bridge T extends from one edge of the recess to the other.

Having thus described my invention, what I claim as new, and desire to secure by Letters Patent, is—

The design for a railroad-frog as herein shown and described.

EDMUND S. WILGUS.
